Patented Apr. 8, 1924.

UNITED STATES PATENT OFFICE.

RAYMOND DAY WHEELER AND OCTAVE DEGRENIER, OF SOUTHERBRIDGE, MASSACHUSETTS, ASSIGNORS TO AMERICAN OPTICAL COMPANY, OF SOUTHERBRIDGE, MASSACHUSETTS, A VOLUNTARY ASSOCIATION OF MASSACHUSETTS.

LENS-MARKING DEVICE.

No Drawing.

Application filed August 2, 1922. Serial No. 579,287.

To all whom it may concern:

Be it known that we, RAYMOND DAY WHEELER and OCTAVE DEGRENIER, citizens of the United States, residing at Southbridge, in the county of Worcester and State of Massachusetts, have invented certain new and useful Improvements in Lens-Marking Devices, of which the following is a specification.

10 This invention relates to new and useful improvements in ophthalmic lenses and more particularly to a novel and improved commercial lens and to the process of producing the said article.

15 At the present day it is somewhat difficult to distinguish the various types and grades of lenses placed upon the market by the various manufacturing concerns and the main object of our invention is to produce a new 20 and improved method for marking lenses whereby to distinguish the various grades and types by the use of characters, letters and the like which are adapted to be marked upon the polished surface of the lens and 25 normally remain invisible but which are rendered visible thru the application of moisture applied to the surface of the lens.

30 A further object of the invention is the provision of a method wherein a lens is produced having portions of its surface mechanically modified whereby the different portions of the surface will be provided with 35 different hydroscopic properties.

With the above and other objects in view 40 the invention consists in the novel features of construction, the combination and arrangement of parts hereinafter more fully set forth in the following specification and it is to be understood that we may make 45 any modifications in the structure or steps hereinafter described within the scope of the appended claims without departing from or exceeding the spirit of our invention.

45 In the carrying out of our invention we first construct a lens from ordinary crown or flint glass or a suitable combination of both, surface it in the usual manner on either one or both faces, as preferred.

50 After the lens has been finally finished on at least one surface it is in condition for the carrying out of our process, which consists in applying to the finished surface of the lens suitable markings in the form of

characters, letters, words, symbols, or the like, thru suitable mechanical mechanism.

55 The words, characters, symbols, etc., are applied to the finished surface of the lens by means of a diamond having a ball point which is passed over the polished surface of the lens under pressure so that the ball point of the diamond will tend to crowd down the molecules of the top surface and cause a molecular change in the polished surface of the glass, thus mechanically modifying the hydroscopic properties of the 60 lens, whereby the modified parts will present a different appearance from the adjacent 65 surface when moistened by the breath.

This surface modification does not destroy any of the polish of the surface of the 70 glass and is invisible under ordinary circumstances but is one which will affect the physical condition of the surface in such a manner that upon subjecting the same to slight moisture such as the moisture of the 75 breath when blowing upon the glass, the difference in hydroscopic properties of the surfaces will cause the moisture, as is usual, to condense in globules, but the condensated 80 globules on the modified part will be different as to size from those on the remainder of the lens, with the result that light striking the surface will be differently affected so that the letters, characters, or symbols 85 will clearly stand out as distinct from the remainder of the lens and may be readily preserved so long as the surface moisture endures but will entirely disappear after 90 the lens surface dries off.

The application of our improved marking is applied with a ball pointed diamond, as heretofore set forth, and is preferably applied under pressure with the diamond holder normal to the surface being marked 95 so as to force the rounded end or ball point of the diamond on the surface of the glass and eliminate possible scratching by side contact. Various ways and means may be provided for guiding the diamond over the lens, or it may be rotated to accentuate the burnishing action of the pressure of the ball point.

We claim:

1. The art of invisibly marking polished glass surfaces consisting in mechanically modifying the hydroscopic properties of the 100 105

surface by crowding down the molecules of the top surface, with a substance harder than the glass surface, whereby a molecular change is produced.

5. 2. The art of invisibly marking glass surfaces consisting in moving a diamond over the surface under pressure, whereby a molecular change is produced.

10. 3. The art of invisibly marking polished glass surfaces consisting in modifying the hydroscopic properties of the surface by moving a blunt point instrument over the surface under pressure, thereby crowding down the molecules of the top surface so 15 that a molecular change is produced in the said surface.

4. The art of invisibly marking polished

glass surfaces consisting in moving a blunt point diamond over the surface under pressure whereby to mechanically modify 20 said surface and produce different hydroscopic properties.

5. An ophthalmic lens having a polished surface, a portion of which is mechanically modified by a blunt point tool, whereby 25 the different portions of the surface have different hydroscopic properties.

6. An ophthalmic lens having a portion of its polished surface crowded down under pressure from a blunt point diamond, 30 whereby the different portions of the surface have different hydroscopic properties.

RAYMOND DAY WHEELER.
OCTAIVE DEGRENIER.
